Invention

Henry N. King

United States Patent Office.

HENRY N. KING, OF ADRIAN, MICHIGAN.

Letters Patent No. 75,552, dated March 17, 1868.

IMPROVEMENT IN ADJUSTABLE JAW FOR VISE.

The Schedule referred to in these Letters Patent and making part of the same.

TO WHOM IT MAY CONCERN:

Be it known that I, HENRY N. KING, of Adrian, in the county of Lenawee, and State of Michigan, have invented a new and useful Improvement in Adjustable Jaws for Vises; and I do declare that the following is a true and accurate description thereof, reference being had to the accompanying drawings and to the letters of reference marked thereon, and making a part of this specification.

Figure 1 is a side view.

Figure 2 is a top view.

Figure 3 is a vertical sectional view; and

The same letters refer to like parts in each view.

The object of my invention is to so construct an adjustable vise-jaw, that bevelled articles may be firmly held in any position required for work.

To accomplish this end, I will now describe my invention as attached to a jaw of an ordinary vise, and in such a manner that those skilled in the art can manufacture it.

A represents the stationary jaw of a vise, and B the movable jaw. To the inner side of the jaw, B, I attach a metal plate, C. Through the jaw B and plate C passes the bolt D, upon the inner end of which is cast the ball E. Before the bolt is passed through, as above described, the collar F is slipped over it, with a hole through it that fits over the ball, but not large enough for the ball to pass through it. After the bolt is passed through the jaw and plate, as described, the collar F is fastened in any suitable manner to the plate G, provided in the centre with a concavity sufficiently large for the ball to play easily within it. The plate G is then attached to a face-plate, H. Upon the top and at either side of the collar F, I attach, by proper fastenings, the adjustable stops I I I, which, when open, hold the face-plate H parallel with the face of the stationary jaw A. By closing either of the side stops, the face-plate will assume a horizontally angular position, as may be desired, and by closing the upper stop, it will assume a perpendicularly angular position to the stationary jaw A. The metal plate C is so constructed that it has a projecting standard, J, upon the top of which are fitted the parts above described, in such a manner as to allow the parts to work in the way referred to, holding them steady and in place at all times.

My object in attaching the stops I I I to the plate G, instead of the plate C, is so as to be able, in attaching the whole to an iron vise, to do away with the plate C, and attach the whole to the movable jaw of the vise, riveting the standard J directly to the jaw of the vise.

What I claim as my invention, and desire to secure by Letters Patent, is—

The combination of the stationary jaw A, the movable jaw B, the plate C, the bolt D, the ball E, the collar F, the plate G, the face-plate H, the adjustable stops I, and the projecting standard, when constructed, arranged, and operating substantially as and for the purposes herein set forth.

HENRY N. KING.
